UNITED STATES PATENT OFFICE.

CLARENCE LE ROY PARKS, OF SEATTLE, WASHINGTON.

PHOTOPRINTING-BOX.

1,389,268.

Specification of Letters Patent. Patented Aug. 30, 1921.

Application filed June 23, 1919. Serial No. 306,060.

To all whom it may concern:

Be it known that I, CLARENCE LE Roy PARKS, a citizen of the United States, and resident of the city of Seattle, county of 5 King, State of Washington, have invented certain new and useful Improvements in Photoprinting-Boxes, of which the following is a specification.

My invention relates to photograph printing boxes of that class wherein artificial light is employed to make prints from roll or pack films; the principal object of the invention being to provide a device of this character whereby printing may be done in 10 a rapid and expeditious manner and prints and negatives may be released from printing position and discharged separately to provide an easy separation.

It is also an object of the invention to 20 provide a numbering mechanism that will operate in conjunction with the printing mechanism so that each print will, at the time of printing, be given a number which may be made to correspond to a number 25 given a printing order so as to provide commercial printers with an easy means of identifying work from different customers.

In accomplishing these objects I have provided improved details of construction, the 30 preferred forms of which are illustrated in the accompanying drawings, wherein—

Figure 1 is a perspective view of a photograph printing machine constructed according to the present invention.

Fig. 2 is a vertical section of the same 35 particularly illustrating the platen operating mechanism.

Fig. 3 is an enlarged sectional view of a 40 part of the box showing the platen in closed position.

Fig. 4 is a similar view showing the platen in open position and the film clamp raised.

Fig. 5 is a transverse section through the 45 same parts on the line 5—5 in Fig. 3.

Fig. 6 is a plan view of the platen and film holding clamp, particularly illustrating the film numbering mechanism.

Fig. 7 is a view of the circuit breaking and closing members.

50 Referring more in detail to the drawings: 1 designates a box or housing which is mounted preferably in an inclined position as shown within a suitable opening 20 in the top of a table 2; the latter being of 55 such height that a person may operate the

machine with convenience when sitting at the front of the table.

Hinged to the upper edge of the box is a cover 10 having a rectangular opening 11 therein covered by a glass plate 12 that is 60 set flush with the upper surface of the cover and is of sufficient size that negatives of the usual dimensions may be easily accommodated.

Mounted within the box is a suitable 65 source of light as a lamp 3 and a reflector 30 whereby light is furnished and directed properly through the glass to effect the printing; the lamps being electrically connected with a source of electricity, as will 70 presently be described, so that light is furnished at the proper time by certain operations of the mechanism.

Hingedly attached to the cover 10 above the opening 11 is a film holding clamp 4 75 comprising relatively long and short legs 40—41, respectively, which are hinged at their upper ends in such a manner that the leg 40 extends along one side and adjacent the edge of the printing opening, while the 80 leg 41 terminates adjacent the upper edge and at the opposite side of the opening. The two legs are connected by a transverse bar 42 which serves, with the lower portion of the leg 40, as means for holding a film, 85 which may be placed thereunder, in proper position for printing.

Thin metal strips 43 are fixed along the inner edges of the leg 40 and bar 42 which project slightly over the printing opening 90 to form the mat for margining the print at these sides, while the margins on the opposite edges are made by proper adjustment of a slide plate 5 secured by a bolt and thumb nut connection to a transversely slidable 95 member mounted in the top 10 so that adjustment of the plate may be made either horizontally or vertically with relation to the stationary mat members so that negatives of all sizes may be accommodated. 100

When a film is placed in the machine for printing its upper and one side edge are held beneath the matted edges of the clamp 4 by the weight of these members, and when printing is finished the film is released by a 105 slight raising of the clamp and it slides from position so that another film may be inserted before the clamp is lowered.

Raising of the clamp members is done through mechanism which is connected with 110

a knee lever 6 that is pivotally fixed at one side of and adjacent the front of the table in such position that it may be actuated outwardly against the pressure of a spring 61 5 to draw on a cable 62 which is extended over suitable rollers 63 to the outer end of a lever 64 which is pivotally suspended from the under side of cover 10. The inner end of the lever supports a post 65 which extends 10 through the cover 10 and engages the under side of the clamp leg 40 in such a manner that, through the mechanism just described, actuation of the knee lever will raise the clamp sufficiently to release a film held thereby and permit the insertion of a new film. 15

When the film has been placed properly beneath the clamp member and the plate 5 has been adjusted to a position to give the print a desired margin, the print, or sensitized paper is placed thereon; the latter being placed closely within the angle of the leg 40 and bar 42. The means for holding the paper in this position before the platen is lowered comprises a small leaf or finger 20 7 mounted on a short rocker shaft 70 that extends through the leg 40 and at its outer end has a crank arm 71, to which is attached a tension spring 72 which acts to hold the leaf against the paper. The leaf is set within 25 a notch in the cross bar 42 so that it will not interfere with movement of the platen to and from position.

Pivottally mounted on a cross rod 73 which extends between the legs 40—41 of the clamp 35 member are the ends of straps 8 which carry a platen 80 that may be moved to compress the paper and film against the glass and after each printing operation automatically moves to open position.

40 The means for operating the platen consists of a foot lever 81 that is pivotally supported from its forward end and at its free end has a cable 82 attached thereto which extends over a roller 84 fixed to the lower 45 corner of the box 1 and rollers 85 mounted between spaced standards fixed at the rear of the table, and at its end is attached to a link 86 which comprises the outer end of a series of links whereby the platen is moved to 50 closed position. The link 86 being pivotally fixed at its lower end between the standards and at its upper end is hingedly connected by a short link 87 with a lever 88, mounted on a block 89 which is hingedly connected 55 through a short link 83 with the platen. It will be seen by referring to Fig. 2 that by applying pressure on the foot lever 81 the link 86 will be carried upwardly at its free end and through the lever 88, and short links 60 87 and 83 will move the platen on its mountings to its closed position.

Fixed on the upper side of the platen is an upwardly curved and rearwardly extending finger 74, which is adapted, when the platen 65 nears its complete open position, to engage

the central crank portion 76 of a cross shaft mounted between the legs 40—41 of the clamp 4, so that the said shaft will be rocked in such a manner that a crank arm 77 at its outer end will be carried rearwardly and, 70 through a link 78 which connects the arm 77 and the arm 71 of the shaft 70, will similarly revolve the latter shaft to raise the print holding finger 7 to open position. It being apparent that with this connection the 75 finger will release a print as the platen moves to open position and will close when the platen has moved but a short distance toward closing position which enables the operator to place the print and remove his 80 hand before the platen closes thereover.

Connected with the link 88 and rear edge of the box cover 10 are tension springs 18 whereby the platen is lifted to open position 85 as soon as pressure is removed from the foot lever.

At the front of the table is a compartment 13 for receiving the prints as they are released, which enter the compartment through an opening 14 adjacent the front of 90 the box. This opening is provided with a door 15 which is normally held in open position by a post 16 which has connection with the cable 62 so that prints when released from position will slide directly into the 95 compartment, but when the knee lever is actuated to raise the clamp to release a film the door is moved to closed position and the film will slide thereover against a stop at the front of the table. In this manner the 100 films and prints are kept separate.

Connection with the lamps is made through wires 33—34 and controlled by a switch 35 on the cover 10. Normally the electrical connection through the wire 33 is 105 broken so that light is furnished only at a time when the platen is completely closed. This is effected by placing spaced contact members 36—37 in the circuit (Fig. 7) between which a circuit may be closed by a 110 spring like bridge member 38 which normally does not engage these members but is pressed into contact therewith by the link 86 as it is swung upwardly during the 115 platen closing operation.

In order that each print may be given an identification number I have mounted a type carrying device 90 on the platen in such a manner that the type are exposed on the under face thereof so that on each compression a number will be stamped on the back of the print. The stamp device 90 is carried by a yieldable member 91 and extends through a suitable opening 93 on the platen. Ink is applied to the type by 120 means of an ink pad 94 carried on a swinging arm 95 mounted on a post 96 on the clamp leg 40. A rocker post 97 is mounted in the clamp member in such a manner that it will be engaged by a platen as it moves 125 130

to open position and through a connecting link 98 will throw the arm to bring the ink pad against the type. As the platen moves to closing position the pad arm is moved 5 outwardly therefrom by a spring 99 which is fixed at one end to the post 96 and at its opposite end to the post 97.

What I claim as my invention is:

1. A photograph printing machine comprising a supporting table having an opening in its top and a print receiving compartment below said opening, a door for said compartment adapted to close said opening and means for holding said door 15 normally in open position, a lamp box mounted on said table provided with an inclined cover, film and print holding clamps mounted on said cover, means for releasing the print holding clamp to deliver prints 20 into said compartment and means for simultaneously releasing the film clamp and closing said compartment door.

2. A photograph printing machine comprising a supporting table having an opening 25 in its top and a print receiving compartment below said opening, a door for said opening and means for holding said door normally in open position, a lamp box mounted on said table provided with an 30 inclined cover having an opening therein, a translucent plate for said cover opening, a film holding clamp mounted adjacent said cover opening, a print holding member on said clamp, a platen and mechanism for 35 operating the same toward and from said opening, and mechanism operable by the platen as it moves to open position to actuate the print holding member to releasing position to deliver prints into said table 40 compartment, means for moving the film clamp to releasing position and co-operating means for simultaneously closing the compartment door of said compartment.

3. A photograph printing machine of the 45 character described comprising a printing box provided with an inclined cover having an opening therein, a translucent plate for said opening, a hingedly mounted platen adapted to move toward and from said 50 opening and mechanism for operating the same comprising a lever pivotally supported

between its ends from the box cover, a relatively short link hingedly connected at its ends to the platen and outer end of said lever, a second lever having a pivotally fixed 55 end and a movable end, a second link hingedly connecting the movable end of the second lever with the inner end of the first named lever and a cable fixed to the second lever to swing the same on its pivotal mounting to rock the first lever on its mounting and thereby actuate the platen toward said opening.

4. A photograph printing machine of the character described comprising a printing 60 box provided with an inclined cover having an opening therein, a translucent plate for said opening, a hingedly mounted platen adapted to move toward and from said opening and mechanism for operating the same 65 comprising a lever pivotally supported between the ends from the box cover, a relatively short link hingedly connected at its ends to the platen and outer end of said lever, a second lever having a pivotally 70 fixed end and a movable end, a second link hingedly connecting the movable end of the second lever with the inner end of the first named lever and a cable fixed at one end to the second lever and at its opposite end 75 to a foot lever and operating over guide rollers to draw upwardly on the second lever as said foot lever is depressed to move the platen to a closed position, and a spring attached to the first named lever and to said 80 box cover for moving the parts to initial position when pressure is removed from the foot lever.

5. A photograph printing machine of the character described comprising a printing 85 box provided with an inclined cover having an opening therein, a translucent plate for said opening, a clamp for holding a film over said plate, a clamp finger for holding a printing paper over said film, a platen 90 movable toward and from said opening, and a type carrying member yieldably mounted in said platen and movable therewith for the purpose set forth.

Signed at Seattle, Washington, this 12th 100 day of June, 1919.

CLARENCE LE ROY PARKS.
